ROCKER FOR INFANT-CARRYING DEVICES

Gordon H. Strom, Charles Lichter, and Paul Rusincky, New York, N. Y., assignors to Automatic Rock-A-Bye, Inc., New York, N. Y., a corporation of New York

Application August 1, 1950, Serial No. 176,955

5 Claims. (Cl. 185—37)

1

This invention relates to a rocker for infant-carrying devices such as perambulators and cradles.

It is an object of the present invention to provide an improved device of the character described which will rock a baby carriage or cradle without an attendant.

It is another object of the present invention to provide a device of the character described which is easily attachable to or detachable from a perambulator or the like.

It is another object of the present invention to provide a device of the character described which is simply and inexpensively manufactured.

It is another object of the present invention to provide a device of the character described which is safe and fool-proof.

It is another object of the present invention to provide a device of the character described which will be of substantial value to the parents of infants in that it eliminates the need to constantly rock infants.

It is another object of the present invention to provide a device of the character described the power unit of which is self-contained.

It is another object of the invention to provide a device of the character described which is dependable, and efficient in operation.

Other objects of my invention will in part be obvious and in part will be pointed out herein-after.

My invention accordingly consists in the features of construction, combinations of elements and arrangements of parts which will be exemplified in the device hereinafter described and of which the scope of application will be indicated in the appended claims.

In the accompanying drawings in which is shown one of the various possible embodiments of my invention,

Fig. 1 is a fragmentary sectional view of an end of a perambulator with a device embodying the present invention attached;

Fig. 2 is a rear view of the device shown in Fig. 1;

Fig. 3 is a bottom view of said device;

Fig. 4 is a sectional view taken substantially along the line 4—4 of Fig. 1;

Figs. 5, 6 and 7 are sectional views taken substantially along the lines 5—5, 6—6 and 7—7 respectively of Fig. 4;

Figs. 8 and 9 are enlarged sectional views taken substantially along the lines 8—8 and 9—9, respectively, of Fig. 7; and

Fig. 10 is an enlarged sectional view taken substantially along the line 10—10 of Fig. 1.

2

Referring now in detail to the drawings, and particularly to Figs. 1, 2, 3, and 10, the reference numeral 20 denotes a device embodying the present invention. Said device includes a casing 22 substantially in the shape of a box with an open front 24. Said open front is of rectangular configuration, being of the same shape as the top wall 26. For purposes of appearance, the bottom edges of the side walls 28 are curved 5 concavely with respect to the open front 24, as is shown in Fig. 1. The back wall 30 of the casing likewise is rectangular but is bent to fit the contour of the edges of the side walls. The shape of the container as viewed from the side 10 is roughly trapezoidal. The casing may be fabricated of any suitable material, for example sheet steel, and the various parts thereof are held together in any conventional manner by riveting or welding.

A sector 32 is hinged to the top edge of the open front of the casing. This sector comprises a bottom wall 34 curved to fit the casing, triangular side walls 36 which taper upwardly, and a flat back wall 38. Slots 40 are formed in the bottom wall to slidably accommodate clamp bolts 25 42 in the lower end of the back wall of the casing.

Said bolts 42 freely extend through openings in the casing through the slots 40 and are screwed 30 into tapped bores in a metal strip 44. The bottom wall 34 of the sector is slidable between the strip 44 and the casing so that by tightening the bolts 42, the sector may be clamped in any 35 position of extension from the casing. The sector is fabricated of any suitable material, e. g. sheet metal. A foam rubber pad 46 may be placed on the exterior surface of the back wall of the sector to prevent marring of a cradle or carriage when the device is attached to the same.

Means is provided to enable the casing to be rapidly attached to and detached from a carriage or the like. Said means comprises a handle 48 including a strip of metal curved to J-shaped cross-section. The inside of the handle 45 is lined with foam rubber 50. Arms 52 integral with the ends of the handle are adjustably attached to the casing as follows: the end of each arm is formed into an annular disk 54. A stud 56 of considerably less diameter than the opening in the disk extends through said opening and screws into the casing. The stud has a large knurled head 58 located on the outside of the casing. Washers 60, 62 are disposed on each end of the disk 54 and are of smaller diameter 55 than said knurled head 58. Between the outer washer 60 and the head of the stud, a plate 64

with a circular skirt 66 is interposed. The sheet conceals the washers and disk and is slotted to pass the arms 52. The plate is of larger diameter than the washers and lesser diameter than the head of the stud. When the knurled head 53 is turned, the stud screws into the casing and the washers clamp the disk 54 between them. The skirt 66 is of such height that it does not touch the casing when the knurled head is fully tightened. The diameters of the openings in the washers are such as to accommodate the stud with very little play. The outer diameters of said washers exceed the size of the opening in the disk.

The rocker 20 is hung on a carriage end 68 as shown in Fig. 1. The position of the rocker is adjusted by means of the structure described in connection with the attachment of the handle to the casing, this structure being specially designed for such adjustment. The sector is extended until it abuts the carriage so that the rocker is in frictional engagement therewith. The sector is held in place in the casing by tightening the clamping bolt 42. The shape of the carriage will govern the adjustment of the handle and its distance from the casing.

Referring now in detail to Figs. 4 and 5, S indicates a spring of a conventional spring motor employed to furnish the motive power necessary to the operation of the present invention. A motor frame 70 is attached to the sides of the casing. The outer end of the spring is anchored to the frame. A gear 72 is actuated by said motor. A second gear 74 is caused to turn by motion of said first gear 72 which engages a pinion gear 76 on the same shaft as the second gear. The second gear meshes with a pinion 78 which is on the same horizontal shaft 79 as another gear 80. Mounted to turn on the same shaft as and to turn with the gear 80 is a heavy weight 82 the center of gravity of which is eccentrically disposed relative to said shaft. Desirably, and as shown, the weight is concentrated in the rim 84 so as to obtain a maximum unbalance. By means of the above-described reduction gear train, the weight is caused to revolve, and it is the rotation of this off-center weight which produces two periodically varying thrusts, one horizontal and one vertical. These thrusts are imparted to anything to which the device is attached.

To enable rotation of the weight about its horizontal axis to be started easily without employing a heavy duty spring motor, means is provided to counter-balance the torque created by said off-center weight. Said means comprises an eccentric 86 affixed on the same shaft as the weight. An eccentric strap 88 engages the eccentric and ball bearings are provided between the same. The eccentric strap is integral with an eccentric rod 90 rotatably attached to a bell crank lever 92. The latter is pivoted on the frame at Y. A short arm 94 of the bell crank lever is disposed at an obtuse angle to a long arm 96 which is attached to the eccentric strap. One end of a tension spring 98 is attached to the short arm 94. The other end of said spring is anchored at an adjustable link 100 carried by the frame. The spring 98 exerts enough force in the linkage system shown to balance the torque caused by the pull of gravity on the weight. More specifically, by urging said short arm toward the point where the spring is anchored, the long arm is biased upwardly. It in turn exerts an upward force on the eccentric rod which pulls up on the

eccentric thus exerting a torque which counter-balances the static torque developed by the off-center weight.

Means is provided to adjustably regulate the period of the varying thrusts. Means also is provided to stop and start the rocker. These means, best shown in Figs. 6-9, include a gear 102 meshing with the gear 80. Gear 102 operates a combined governor and brake mechanism to control the speed and stop the motion of the rotating eccentric weight. The governor comprises a box 104 attached to the frame. Several weights 106 mounted in the box are between the ends of leaf springs 108. Each spring is attached at one end to a collar 110 pinned to a shaft 112 which is rotated by said gear 102. A sleeve 114 is slideable on the shaft 112. Said sleeve has a circular flange 116 perpendicular to the shaft. The other ends of the leaf springs are attached to the sleeve.

Friction shoes 118, 119 are held facing the flange in two channels 120 which are pivoted on a rod 122 located below the shoes. Hairpin springs 124 bias the channels in a counterclockwise direction as viewed in Fig. 6. Above the pivot rod the channels are formed into forks 126 which abut controls 128, 130. The hairpin springs thus maintain the fork of each channel against its associated control and bias each shoe toward the flange 116. Control 128 when pushed into the box moves its associated shoe 118 away from the flange 116. When pulled out, it allows the hairpin spring to rotate the channel so that the portion above the pivot pushes the shoe against the flange 116. The flange rotates with the shaft 112 because the leaf springs 108 to which said flange is attached are at their other ends pinned to the shaft as described above; thus, pulling control 128 out stops the whole mechanism by braking the shaft to which the gear 102 is affixed.

Control 130 has a male threaded extension which screws into a tapped opening 132 in the frame 70. By rotating this control the distance from the second shoe 119 to the flange 116 is varied. The governor operates as follows: When the shaft 112 rotates, the weights 106 are urged outwardly by centrifugal force causing the leaf springs to bow. The sleeve 114 and flange 116 thereby are shifted toward the shoes, the degree of movement being proportional to the rotative speed of the shaft 112. The shoe 118 used for braking purposes is beyond the range of movement of the flange when the control 128 is in its "on" position, but the second shoe, i. e., the speed control shoe 119 is within said range of movement, and when it is contacted by the flange, the speed of rotation of the governor shaft 112 is momentarily checked. This allows the bowed springs to partially straighten, the centrifugal force being slightly weaker when the governor shaft slows down. Equilibrium quickly is reached with the speed control shoe lightly dragging on the flange. In this way, the rotative speeds of the shaft, gear trains and off-center weight are adjustably controlled. The farther in the control 130 is screwed, the greater is the distance the flange 116 must move to contact the speed control shoe 119, and thus the greater will be the speed that is developed.

The spring motor is wound by a manually operable crank which detachably engages a stub-actuating shaft 134 extending from the frame 70.

It is apparent that a device is provided by the present invention as above described which is easily attached to a carriage, will impart a

rocking motion thereto and the motive power of which is self-contained. The rate of rocking imparted is controlled by a governor.

It thus will be seen that there has been provided a device which achieves all the objects of the invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described the invention, we claim as new and desire to secure by Letters Patent:

1. A device for rocking a perambulator or the like comprising a centrifugal weight, means to mount said weight for rotation about an axis eccentrically disposed with respect to the center of gravity of the weight, means to rotate said weight about said axis so as to obtain centrifugal action thereby, and means to detachably hang said mounting means on the edge of a perambulator or the like.

2. A device for rocking a perambulator or the like comprising a centrifugal weight, means to mount said weight for rotation about a horizontal axis eccentrically disposed with respect to the center of gravity of the weight, means to rotate said weight about said axis so as to obtain centrifugal action thereby, means to counterbalance the dead weight torque created by said eccentric weight, and means to attach said mounting means to a perambulator or the like.

3. A device for rocking a perambulator or the like comprising a centrifugal weight, means to mount said weight for rotation about an axis eccentrically disposed with respect to the center of gravity of the weight, means to rotate said weight about said axis so as to obtain centrifugal action thereby, adjustable governor means to

control the rotative speed of said off-center weight, and means to attach said mounting means to a perambulator or the like.

4. A device for rocking a perambulator or the like comprising a weight, means to mount said weight for rotation about a horizontal axis eccentrically disposed with respect to the center of gravity of the weight, means to rotate said weight, means to counterbalance the dead weight torque of said weight, said means comprising a spring and a linkage to transmit force from said spring to said weight, and means to attach said mounting means to a perambulator or the like.

5. A device for rocking a perambulator or the like comprising a weight, means to mount said weight for rotation about a horizontal axis eccentrically disposed with respect to the center of gravity of the weight, means to rotate said weight, means to counterbalance the dead weight torque of said weight, said means comprising a spring and a linkage to transmit force from said spring to said weight, said linkage comprising an eccentric mounted to turn about the same axis as and with said weight, a strap disposed about said eccentric, anti-friction bearings between said eccentric and strap, a bell crank having an arm pivotally attached to said strap, said spring to be mounted to bias the other arm of the bell crank so that said crank exerts an upward force on said eccentric, and means to attach said mounting means to a perambulator or the like.
